Fig. 4.

Fig. 5.

Fig. 8.

Fig. 9.

FIG. 1 is a top view of the unitary shoe-polishing device pictured in assembled relationship in FIG. 2.

FIG. 2 is a side view of the unitary device in assembled relationship showing our original, new design.

FIG. 3 is a bottom view of the same device.

FIG. 4 is a variation of the device pictured in FIG. 2 in that it consists of said device but the bottom dauber-brush is slightly longer and of a lesser diameter than the dauber-brush shown in FIGS. 2 and 3.

FIG. 5 is a bottom view of the device shown in FIG. 4.

FIG. 6 is a bottom view of the device shown in FIG. 4 but it omits the longitudinal side buffer element which cannot in any event be seen in the FIG. 4 drawing.

FIG. 7 is a bottom view of the device pictured in FIG. 9.

FIG. 8 is a top view of the unitary device pictured in FIG. 9.

FIG. 9 is a side view of the device pictured in FIG. 4, but it omits the longitudinal side brush and the bottom dauber-brush is slightly shorter and wider than the dauber-

We claim:

The ornamental design for a unitary shoe-polishing device, substantially as shown and described.
